ABSTRACT OF THE DISCLOSURE

A fluid amplifier including a jet, an interaction region and a receiver. Vent means are provided for the interaction region. Receiver outlets are connected to the interaction region through a receiver intermediate passageway and a receiver inlet passageway which are out of alignment with one another. A vent passageway which is in alignment with the receiver intermediate passageway is provided to receive reverse fluid flow from the receiver.

The invention described herein was made by an employee of the United States Government and may be manufactured and used by or for the Government of the United States of America for governmental purposes without the payment of any royalties thereon or therefor.

The instant invention relates to fluid systems. More particularly, the instant invention relates to an improved fluid jet amplifier.

A fluid jet amplifier as described herein is a no moving parts device which is capable of amplifying fluid signal flows and pressures in much the same manner as its electrical equivalent, the transistor, amplifies currents and voltages. A fluid jet amplifier can utilize either a liquid, a gas, or a combination thereof.

Basically, a fluid jet amplifier is a device wherein an input fluid flowing through a nozzle forms a jet which is caused to flow through an interaction region or cavity wherein the jet may be deflected to one side or another of said region by means of pressures developed in the interaction region by the flow fluids established therein and/or the use of control signals or nozzles located on either side of the jet. Introducing flow at one of the control nozzles causes the cavity pressure on that side of the jet to be raised thus causing the jet to deflect to the other side. Effectively capturing and utilizing the output flow from the fluid jet amplifier is much more difficult than loading a transistor. The usual method consists of placing a pair of receivers immediately downstream of the interaction or cavity region.

In fluid jet amplifiers of the type described herein various problems have been encountered which can greatly effect its performance.

One problem involves the furnishing of a flow restriction between the control line and the cavities of the interaction region of a bistable amplifier. For a Coanda effect fluid jet amplifier to be bistable in operation, some type of restriction must be provided. One method consists of placing an orifice restriction in the control lines leading to the interaction region. The volume in the control signal lines between the orifice restriction and the interaction region can be large in comparison to the volume of the cavities in the interaction region, can reduce switching speeds and cause transient instabilities to occur during switching. It has also been proposed to form the proper orifice restriction by having a control port of narrow width located in close proximity to the side wall of the main jet. However, for the amplifier to have high triggering sensitivity, the sidewalls must be set back from the main power nozzle a small and precisely controlled amount. Inasmuch as the performance of the amplifier is quite

2

sensitive to the amount of the sidewall setback, small manufacturing errors can cause variations in the amplifier performance. Furthermore, a fairly large control signal flow may be demanded even in the absence of a control pressure signal. This quiescent control flow must be taken into account in the design of fluid jet amplifiers. Failure to take this control flow into account can result in inadvertent switching of the amplifier.

Another problem is that the reverse flow exiting from one of the receiver channels toward the interaction region can cause a change in the amplifier's performance. Such a situation is likely to occur if the receivers are connected to a moving piston or if they are connected to a large volume and the jet is suddenly switched from one side to another. Also, blockage or restriction of the receiver output flow can sometimes cause unstable operation. It has been proposed to put a plurality of bleeds in the load. However, this can cause great losses in power. Other proposed solutions include putting a cusp on the splitter in order to create a stabilizing vortex and drilling a hole in the receiver channel at a right angle to the plane of the amplifier. However, this latter method will also cause low power recovery.

It is therefore an object of the instant invention to reduce the sensitivity of a fluid amplifier to receiver reverse flow.

It is another object of the instant invention to provide for a fluid amplifier that is stable under all load conditions.

It is still another object of the instant invention to provide for an improved fluid amplifier that will maintain good pressure and flow recoveries and at the same time be stable under all load conditions.

It is still another object of the instant invention to provide for an improved fluid amplifier wherein the receiver reverse flow is prevented from changing the control pressure and flow required to switch said amplifier.

It is yet still another object of the instant invention to eliminate using large safety factors in computation of control pressures and flows in fluid amplifiers.

It is another object of the instant invention to provide for a fluid amplifier that can be used with a piston type load.

It is another object of the instant invention to reduce the control flow required in the absence of controlled pressure signal in a fluid amplifier.

It is still another object of the instant invention to provide a fluid jet amplifier which requires low control signal pressures and flows and which does not require a small, precisely controlled wall offset at the beginning of the interaction region.

It is another object of the instant invention to provide for a fluid amplifier having large deflection angles and a short interaction region length.

Other objects and many of the attendant advantages of this invention will be readily appreciated as the same becomes better understood by reference to the following detailed description when considered in connection with the accompanying drawings in which like reference numerals designate like parts throughout the figures thereof and wherein FIG. 1 is a schematic elevational section view of one embodiment of the instant invention and FIG. 2 is an enlarged view of the portion of the device shown in FIG. 1 enclosed within the dotted line.

In accordance with this invention the aforesaid and other objects are achieved by designing a fluid amplifier wherein an effective orifice restriction is formed by the edge of the control port with the main jet stream. The control ports or nozzles are located upstream from the interaction region. In addition, the receiver channels are designed so that the mouth of the channels are displaced laterally and pointing away from the interaction region.

The receiver section of the amplifier is further provided with a baffle wall to separate the receiver reverse flow from the entrainment flow to the interaction region of the fluid jet amplifier.

Referring now to the drawings wherein like reference numerals represent like parts there is shown in FIGS. 1 and 2 a fluid amplifier comprising a substantially solid body 10. In the embodiment shown the solid body 10 is fabricated from a transparent plastic. However, any other suitable material possessing suitable strength such as ceramics, opaque plastics, or metals may also be employed. The solid body 10 is provided with a plurality of channels or passage ways through which a fluid may flow. These passageways are either cut, etched or otherwise suitably formed therein. The completed fluid amplifier also includes a cover plate (not shown) which may be fabricated from any of the above-mentioned materials. The cover plate is fastened in a fluid-tight relationship to the solid body by means of screws (also not shown). However, any other type of sealing means such as cement may be employed. In FIG. 1 the holes 21 for receiving the screws or other similar fasteners are shown suitably spaced about the solid body.

The solid body member 10 is comprised basically of three parts. Namely a power and control inlet section, an interaction region, and a receiver section.

The power and control inlet section includes a primary fluid supply port 31 through which a compressor or pump (not shown) supplies a suitable regulated stream of fluid into a primary fluid input chamber 32. A plurality of guide vanes 33 in the form of projections are located within the fluid input chamber 32 to aid in directing and smoothing the stream of fluid into a power nozzle 34.

A pair of secondary fluid supply ports 41, 42 are located on either side of the main power nozzle 34. These secondary ports 41, 42 introduce control signal pressures and flows into their respective connecting control port channels 43, 44. The control port channels 43, 44 in turn connect respectively to a pair of control inlets 45, 46 positioned adjacent to the main power nozzle 34 and the main power stream. Said control inlets 45, 46 introduce control flow into the interaction region through an orifice restriction 51 formed by the edge of the control inlets 45, 46 and the main jet power stream. The walls of the orifices restriction 52, 53 are in substantial alignment with the walls of the main power nozzle 34. The length of the orifice restriction 51 is sized so as to be either equal to or less than one half the width of the main power nozzle 34. This method of providing an orifice restriction enables control flow to be introduced into an interaction region with only a small control pressure and reduces the quiescent control flow demanded by the interaction region when no control pressure is present. The interaction region or section includes an interaction region chamber 61. As shown in FIGS. 1 and 2 the interaction region chamber 61 is formed by a plurality of sidewalls 62, 63, 64, 65 and a pair of interaction region backwalls 66, 67. Interaction region sidewalls 62, 63 are bent at an angle equal to the angular deflection of the main power jet. A pair of interaction region vents 71, 72 are in communication with the interaction region chamber 61 and furnish entrainment flow at ambient pressure to the interaction region. These interaction region vents 71, 72 in turn exit by means of a pair of interaction region vent ports 73, 74 connected to exhaust pressure.

A receiver section or portion is located immediately downstream of the interaction chamber. The receiver portion includes a pointed divider member 81 located immediately downstream of the interaction region chamber 61. The divider member 81 includes a centrally disposed passage way 82 terminating in a center vent port 83 con-

an axis substantially parallel to the interaction region sidewalls 62, 63. The receiver connecting inlet passages 84, 85 in turn exit into a pair of receiver intermediate passage ways 86, 87 at a shallow angle (20° in FIG. 1). The receiver intermediate passages, 86, 87 are displaced laterally from the interaction region 61 and angled such that any reverse flow from them will completely miss the interaction region 61. Because the reverse flow completely misses the interaction region 61, changes in interaction region performance as a result of receiver reverse flow are reduced. By means of this angle between the receiver connecting inlet passages 84, 85 and the receiver intermediate passages 86, 87, any receiver reverse flow can be directed away from the interaction region 61.

To further prevent any receiver reverse flow from either returning to the interaction region chamber 61 or interfering with entrainment flow to the interaction region 61, a pair of receiver vents 91, 92 are located on either side of the receiver connecting inlet passages 84, 85. The receiver vents 91, 92 are in the form of channels which are in substantial alignment with the receiver intermediate passage ways and which terminate in receiver vent ports 93, 94. Each area bounded by a receiver vent 91, 92, its adjacent receiver connecting inlet passage 84, 85 and its adjacent interaction region vent 71, 72 forms a baffle wall 95, 96. By means of the receiver vent 91, 92 in cooperation with the baffle wall 95, 96, any receiver reverse flow will be prevented from travelling down into the receiver connecting inlet passageways 84, 85 or interfering with entrainment flow delivered to the interaction region. This flow pattern is shown schematically by arrows in the channels of FIG. 1. The receiver intermediate passageways 86, 87 in turn exit into a pair of diffuser sections 88, 89 which in turn exit into a plurality of receiver outlets 101, 102, 103, 104, 105, 106 which may be connected into a plurality of arbitrarily chosen loads, such as the control ports of other fluid jet amplifiers, volumes, pistons, bellows, or positive displacement motors.

An amplifier according to the instant invention has been built and tested. Excellent results were obtained with the following power nozzle (34), interaction region (61) and receiver dimensions:

Power nozzle width 31— D_j
 Spacing between interaction sidewalls 64, 65— $2.2D_j$
 Length of interaction region sidewalls 64, 65— $2.2D_j$
 Length of exit portion of interaction region sidewalls 62, 63— $5D_j$
 Angle of receiver inlet passages 84, 85—20°
 Width of center vent port 83— $.813D_j$
 Width of receiver inlet passages 84, 85— $1.3D_j$
 Width of receiver intermediate passages 86, 87— $1.3D_j$
 Width of interaction region vents 71, 72— $.813D_j$
 Width of control ports 45, 46— $.813D_j$

With an amplifier of the above-listed specifications, average control pressures and flows of 7 percent and 5 percent of supply pressures and flows, respectively, were required to switch the power jet. Increasing the control pressure by 60 percent enabled the power jet to be switched into a reverse flowing receiver pressurized at 40 percent of the supply pressure to the main power nozzle 31.

The aforesaid performance figures were obtained with an amplifier having a throat width of .040" and a supply pressure of 1.0 p.s.i.g. The limits on range of pressures were determined by a maximum throat Mach number of .8 and a minimum throat Reynolds number (based on throat width, D_j) of 4000. The ratio of depth of the amplifier's channels to throat width was 1.5.

Obviously many modifications and variations of the present invention are possible in the light of the above teachings. It is therefore to be understood, that within the scope of the appended claims the invention

means in communication with the power inlet means for controllably deflecting said stream of fluid under pressure, an orifice restriction in communication with the power inlet means and located downstream of the control inlet means, an interaction chamber in communication with the orifice restriction and located downstream from said orifice restriction, interaction region vent means in communication with the interaction region chamber for furnishing entrainment flow to said interaction chamber and receiver means positioned downstream of the interaction chamber, said receiver means including receiver vent means for providing a path thereby for receiver reverse flow.

2. The invention according to claim 1 wherein said power inlet means includes a power nozzle and wherein said orifice restriction is in substantial alignment with said power nozzle.

3. The invention according to claim 2 wherein the length of the orifice restriction is one-half the width of the main power nozzle.

4. The invention according to claim 1 wherein said receiver means includes a receiver connecting inlet passage way in communication with the interaction chamber downstream of the interaction region vent means and an intermediate passage way for connecting the receiver inlet passage way into a receiver outlet, said receiver inlet

10
5
passage way being out of alignment with the receiver intermediate passage way and said receiver vent being in alignment with the receiver intermediate passage way.

5. The invention according to claim 4 wherein said receiver inlet passage way intersects the receiver intermediate passage way at an angle of approximately 20 degrees and wherein said receiver vent passage way and said receiver intermediate passage way form an angle of approximately 180 degrees.
